[57] CLAIM

The ornamental design for an insect trap, substantially as shown and described.

DESCRIPTION

FIG. 1 is a front elevational view of an insect trap embodying my new design;

FIG. 2 is a side elevational view;

FIG. 3 is a top plan view;

FIG. 4 is an exploded partial front elevational view;

FIG. 5 is a bottom plan view along line 5—5 of FIG. 4;

FIG. 6 is a top plan view along line 6—6 of FIG. 4; and

FIG. 7 is a bottom plan view along line 7—7 of FIG. 4. The broken lines in FIG. 2 are disclosed for illustrative purposes only and form no part of the claimed article.

FIG. 1

FIG. 2
